UNITED STATES PATENT OFFICE.

BERNARD V. O'NEILL, OF NEW YORK, N. Y.

MUSIC-ROLL CONTAINER.

Application filed January 15, 1921. Serial No. 437,501.

To all whom it may concern:

Be it known that I, BERNARD V. O'NEILL, a citizen of the United States, and a resident of the city of New York, borough of

5 Bronx, in the county of Bronx and State of New York, have invented a new and Improved Music-Roll Container, of which the following is a full, clear, and exact description.

10 This invention relates to containers, and has particular reference to a container or box for music rolls for player pianos.

In the ordinary construction of containers for music rolls now in general use, it is customary to remove the roll from the box when it is desired to operatively associate the same with the piano. This method has many disadvantages due to the failure of the player to return the roll to the proper box, 20 and due to the fact that many of the rolls are placed in the wrong box, resulting in loss of time and endless trouble in locating the desired roll under these circumstances.

The invention contemplates and seeks for 25 its principal object, to provide a container for music rolls which includes a means to permit the playing of the roll without removing the same from the box.

Another object of the invention is to provide 30 a container of the character described, which includes means for effectually supporting itself when operatively associated with the supporting elements whereby to reduce friction to a minimum, and at the same time prevent wear on the container proper.

A further object of the invention resides in the provision of means for preventing the free end of the note sheet from being drawn entirely into the box.

40 The invention further contemplates the provision of a box or container of the character described, which is constructed in such a manner as to facilitate the insertion and assembly of the roll when it is initially placed in the container.

A still further object of the invention is to provide a box or container of the character described which is extremely simple in construction, inexpensive to manufacture, 50 and which is highly efficient in its purpose.

With the above described and other objects in view, some of which will appear more clearly hereafter, reference is made to the following specification, the appended 55 claims, and accompanying drawings, in which—

Figure 1 is a longitudinal sectional view through the box taken approximately on the line A—A of Fig. 2 and illustrating in dotted lines the relation of the music roll 60 and supporting elements therefor.

Figure 2 is a transverse sectional view taken approximately on the line b—b of Fig. 1.

Figure 3 is a perspective view of the container 65 illustrating the manner in which the same is assembled.

Figure 4 is a plan view of the blank from which the container is folded.

Figure 5 is a detailed perspective view of 70 the hook carried by the free end of the note sheet.

Referring to the drawings by characters of reference, 10 designates generally the blank from which the box or container is 75 constructed, and the same includes a solid bottom 11 and the sides 12 and 13, which are adapted to be folded upwardly therefrom at substantially a right angle along the lines 14 and 15. The top 16 is formed 80 integrally with the side 13 and is folded on the line 17 to close the open top of the container. The top is provided with a flap 18 formed integrally therewith at its free side edge and said flap is provided with a locking tab 19 which is designed to engage and coact with the slot 20 in the side 12. The bottom is provided with integral end walls 21 which are adapted to be folded on the line 22 at a right angle to the bottom to 90 overlie the end flaps 23 formed integrally with the sides 12 and 13. The end walls are further provided with flaps 24 at their free ends which are designed to be bent inwardly at a right angle to overlie the upper edges of 95 the flaps 23 and underlie the cover or top 16. The end walls are provided with central apertures 25 disposed at the axial center of the box when folded. The flaps 23 are provided at their outer edges with arcuate 100 notches 26 in order that the same will not obstruct or cover the aperture 25 in the end wall. The side 13 is provided with a longitudinal slot 27 having a notch 28 in one of its side edges disposed at one side of the longitudinal center of the same for a purpose to be hereafter set forth.

The music roll illustrated in dotted lines in Figure 1 is of conventional construction, and comprises the note sheet S which is 110 wound upon the central core, which core is provided at its opposite ends with the usual

flanges F, each of which is formed to provide on its outsides the trunnions T.

In order to provide bearing elements for supporting the container when the roll is in operation, the bearing blocks 28 are employed which are preferably constructed of wood, the same being recessed as at 29 from their upper sides toward the center, and said recesses terminating in a semi-circular wall 30 which is coincident with the axis of the container. In assembling the box and associating the music roll therewith, the free extremity of the note sheet, which is provided with a re-enforcing tab T carrying the eye 31, is inserted through the slot, the eye 31 being first inserted through the slot adjacent the notch 28. The trunnions T of the flanges F are positioned in the recesses 29 of the bearing blocks, the same co-acting with the semi-circular inner end 30 thereof. Preferably, the flaps 23 are glued to the blocks 28 to retain the same in folded condition, and the end walls 21 are glued to the flaps 23. The cover is then folded over the open top of the container and the tab or lock 19 is engaged in the slot 20. The roll and container are then ready for use in connection with a piano.

In use and operation of the roll, the same is inserted with the container in the usual manner in the spool box of the piano, the supporting elements E being inserted through the apertures 25 and engaged with the flanges F in the usual manner. The slot 27 is disposed toward the front of the piano, and the eye 31 is engaged in the usual manner with the hook of the driving spool of the spool box. In order to maintain the container or box in proper position, the bearing blocks 28 are weighted at the upper rear corners as at 32 by an insert of lead or any other suitable material. By this arrangement the box will be normally maintained when in position at the proper angularity to dispose the slot 27 in the proper position to permit of the free running of the note sheet therethrough. The eye 31 is provided with laterally extending bails 33 which serve to prevent the free end of the roll from being wound entirely into the box, and further to readily effect its association with the driving spool.

In playing the roll, the note sheet will be unwound from the roll as it is wound upon the driving spool in the usual manner, the sheet passing through the slot 27. In rewinding the roll after playing the same, the note sheet will be wound upon the roll as the driving spool is unwound.

By this arrangement, it is seen that a container for music rolls is provided which permits of the playing and rewinding of the roll without removing it from the container.

While there has been illustrated and de-

scribed a single and preferred embodiment of the invention, no limitation is necessarily made to the precise structural details, as it is to be understood that variations and modifications which properly fall within the scope of the appended claims may be resorted to when found expedient.

What I claim is:

1. A container for player piano music rolls to afford means to permit of the playing and rewinding of the roll without removing the same from the container, comprising a weighted means carried by the container for balancing the same on the roll while said roll is rotating. 75

2. A container for player piano music rolls to afford means to permit of the playing and rewinding of the roll without removing the same from the container, comprising a weighted means carried by the container for balancing the same on the roll while said roll is rotating, and means provided on the note sheet adapted to coact with the container upon completion of the rewinding operation to cause the container to rotate with the roll. 85

3. A container for player piano music rolls adapted to afford means to permit of the playing and rewinding of the roll without necessitating its removal therefrom, comprising a box having apertured end walls through which the music roll supporting elements of the piano are adapted to extend, said box having a slotted side wall through which the note sheet is adapted to pass, and weighted bearing means at the opposite ends of said box adapted to coact with the opposite ends of the music roll for supporting the box in balanced position from the roll to permit of relative rotation of the roll with respect to the box. 95

4. A container for player piano music rolls adapted to afford means to permit of the playing and rewinding of the roll without necessitating its removal therefrom, comprising a box having apertured end walls through which the music roll supporting elements of the piano are adapted to extend, said box having a slotted side wall through which the note sheet is adapted to pass, weighted bearing means at the opposite ends of said box adapted to coact with the opposite ends of the music roll for supporting the box in balanced position from the roll to permit of relative rotation of the roll with respect to the box. 105

5. A container for player piano music rolls to permit of the playing and rewind. 110

115

120

125

ing of the roll without removing the same therefrom, comprising a box having apertured end walls through which the music roll supporting elements are adapted to extend for engagement with the roll, said box having a longitudinally slotted side wall through which the note sheet is adapted to pass, bearing elements in the opposite ends of said box adapted to bear on the opposite ends of the music roll, and weighted means carried by the container for balancing the same on the roll during the playing or rewinding of the same.

6. A container for a perforated sheet music roll consisting of a box having an opening in one side thereof for the passage

of the sheet, axially apertured end walls adapted to receive the music roll supporting element therethrough, bearing elements disposed within said box adjacent the opposite ends thereof having recesses from one edge terminating in a semicircular wall coincident with the axis of the openings in the end walls for the reception and accommodation of the music roll spool and the music roll supporting elements, and a weight carried by each bearing member at the same side thereof for gravitationally maintaining the box against rotation during the playing of the roll.

BERNARD V. O'NEILL.
